UNITED STATES PATENT OFFICE.

CHRISTIAN J. MEUNIER, OF NEW ORLEANS, LOUISIANA.

DEVICE FOR HOLDING BEDCLOTHES IN POSITION.

Application filed May 22, 1923. Serial No. 640,739.

To all whom it may concern:

Be it known that I, CHRISTIAN J. MEUNIER, a citizen of the United States, residing at New Orleans, in the parish of Orleans and State of Louisiana, have invented certain new and useful Improvements in Devices for Holding Bedclothes in Position; and I do hereby declare the following to be a full, clear, and exact description of the invention, 10 such as will enable others skilled in the art to which it appertains to make and use the same.

This invention relates to devices adapted to hold bed clothes in position over the occupants of the bed, being especially adapted in the retention of the bed clothes in protective position over babies or small children, and equally adapted to insure the protection of sleeping adults.

20 It is generally recognized to be a fact that a great many of the colds inflicted upon human beings are due to the fact that the bed covers become disarranged during the hours of sleep, and the bodies of the occupants of the bed unduly exposed to the relatively cold temperature of the bed room. Babies or small children, whether asleep or awake, are liable to disarrange the covers, resulting in the dangerous exposure heretofore referred to.

One of the objects of my invention, therefore, is the provision of means adapted to be so secured to the bed clothes that the latter will lie in the proper position over the body 35 of the occupant of the bed, and be firmly held in that position against any movement of the occupant's body tending to disarrange the clothes.

Another object of the invention is the provision of a device such as above referred to, 40 which is adjustable to fit beds of any size.

A further object of the invention is the production of such a device which will not interfere in any way with the comfort of 45 the occupant of the bed, whether the occupant is asleep or awake.

Other objects of the invention will be apparent from the following specifications, when read in connection with the drawings 50 forming a part thereof.

In said drawings:

Fig. 1 is a top plan view of a bed equipped with my device.

Fig. 2 is a side view, partly in section, of 55 the clamping devices at the head of the bed.

Fig. 3 is a side view of the clamping devices at the foot of the bed.

Fig. 4 is a side view showing a modified form of the means adapted to be fastened to the bed covers, and

Fig. 5 is a vertical section taken on line 5—5 of Fig. 2.

Now referring specifically to the drawings, the device consists, in part, of two clamping members A and B, the member A being adapted for utilization near the head of the bed and the member B at the foot. Except as hereinafter noted, the two members are similarly constructed.

The member A is made up of two co-operating bars 1 and 2, preferably formed of resilient sheet metal, each bar being inclined downwardly from its top body portion at 3, and terminating in hooked or angled ends 4, adapted to detachably receive 75 the rails 5 of the bed, as shown in Fig. 2, or to be slipped over the edge of the mattress, as shown in Fig. 4.

As shown in Fig. 5, the bar is provided with flanges 6—6, which are carried inwardly and spaced from the body portion, to provide a channel adapted to slidably receive the body of the bar 2. As shown in Fig. 2, the bar 1 is provided with an aperture, and the body of the bar 2 provided 85 with several spaced apertures, and a pin 7 is adapted to be extended through the aperture in the bar 1, and any one of the apertures in the bar 2, whereby to retain the two bars in any position to which they are adjusted to fit beds of different widths, as will be understood. The pin 7 may be of any desired construction, adapted to hold the two bars in position.

Surrounding the bars 1 and 2 is a strip 95 of heavy cloth 8, which may be detachably secured in position in any suitable manner, such as by hooks and eyes, buttons, etc., or which may be permanently sewed in position. The strip 8, after being so connected 100 terminates in an end 9, directed towards the foot of the bed, and, at spaced intervals on said end 9, are fastened safety pins 10, or other safety securing devices adapted for connection to the bed clothes.

The foot member B is practically identical in all respects with the member A, the exception being that the bars 1 and 2 are not provided with the downwardly extending portions 3, the bars therefore lying in 110

a plane adjacent the plane of the top cover of the bed. It is similarly provided with the strip 8, the extension 9 and the retaining members 10, however.

- 5 Fig. 4 shows a modification of the strip 8, wherein a plurality of strips of cotton tape 11 are secured at their tops, to the members A and B. The strips 11 may be provided with nickeled rings 12, adapted 10 to fit loosely in apertures formed in the members 1 or 2, when it is desired to prevent any lateral movement of the strips, or the rings may be slidably mounted on the members A and B. It is understood that 15 the rings 12 are swingingly connected to the members A and B. To the bottom of each strip 11 is connected a safety pin 10, or other fastening device, whereby the bed clothes may be readily secured to said 20 strips 11.

In the application of my device, as described, the bar 1 may be secured to the side rail 5 or to the mattress, by merely placing the hooked or angled end 4 around 25 said rail or over the edge of said mattress. The end of the bar 2 is then slipped in between the flanges 6-6, and the end 4 of the bar 2, then lowered and pushed inwardly until said end operatively engages 30 the mattress or the rail 5 on that side of the bed. The pin 7 is then passed through the apertures in the bars 1 and 2, and retains said bars in their adjusted positions. The members A and B are then pushed 35 backwardly or forwardly, longitudinally of the rails 5, or the mattress, until they are in their proper positions, the member A at the head of the bed and the member B at the foot, it being noted that the resiliency 40 of the metal of the bars 1 and 2 will serve to resiliently retain the members in the positions to which they have been adjusted.

After the members A and B have been properly adjusted, longitudinally of the bed, 45 the ends 9 of the strips 8 will be found to be resting on the top bed covers, and the pins 10 may be secured to said covers. It is to be noted that the pins 10 may be secured as described, at a point substantially 50 removed from the top edge of the bed cover, thereby leaving free a portion of the clothes sufficient to cover the neck and shoulders of the occupant. Manifestly, the member A may be so adjusted, prior to connection 55 with the bed clothes, as to vary the extent of that portion of the clothes left between the point of attachment thereof and the head of the bed.

It will be noted that the arched construction of the member A, as indicated, 60 permits freedom of movement of the body of the bed occupant, but that such movement can not disarrange the clothes from parallelism with the bed or mattress, because of 65 the connection of the strip 8 to the clothes.

The member B is similarly connected to the bed rails or mattress and detachably secured to the bed clothes, and is raised just enough above the top cover to provide for movement of the feet or limbs. If desired, 70 it may rest directly upon the bed clothes and be positioned adjacent the foot of the bed, beyond reach of the feet of the occupant. Its primary object is to retain the clothes in position, although, in some instances, and when the occupant of the bed is an adult, the section B may be dispensed with and the section A relied upon to preserve the clothes in position.

From the foregoing it is obvious that I 80 have produced a device of the class described, which will not only efficiently serve the purpose for which it is provided, but which is easily adjustable longitudinally of the bed, to positions desired, and is also adjustable laterally to adapt it to beds of different widths. It may be easily detached for straightening the bed, as will be understood.

Modifications of the herein-described 90 structure may be suggested to those skilled in the art, but my invention includes all such modifications and embodiments as fall fairly within the scope of the appended claims.

I claim:

1. A device of the character described, comprising two bars of resilient material provided with hooked ends adapted for connection to bed rails or mattress, said bars being extended upwardly from said ends and adapted for telescopic engagement each to each, substantially as described.

2. A device of the character described, comprising two bars of resilient material provided with hooked ends adapted for connection to bed rails or mattress, said bars being extended upwardly from said ends and adapted for telescopic engagement each to each, and means for securing said bars in different positions of adjustment, substantially as described.

3. A device of the character described, comprising two bars of resilient material provided with hooked ends adapted for connection to bed rails or mattress, said bars being extended upwardly from said ends and adapted for telescopic engagement each to each, and means for securing said bars in different positions of adjustment, said means comprising apertures in the bars and a retaining member adapted for insertion in the other bar and adapted to prevent relative movement between said bars, substantially as described.

4. A device of the character described, comprising two bars of resilient material provided with hooked ends adapted for connection to bed rails or mattress, said bars being extended upwardly from said ends

and adapted for telescopic engagement each to each, and means connected to said bars adapted to be detachably connected to the bed clothes, substantially as described.

- 5. A device of the character described, comprising two bars of resilient material provided with hooked ends adapted for connection to bed rails or mattress, said bars being extended upwardly from said ends
- 10 and adapted for telescopic engagement each to each, and means connected to said bars adapted to be detachably connected to the bed clothes, said means comprising an element swingingly mounted on said bars, and
- 13 carrying means whereby to fasten said element to said clothes, substantially as described.

6. Bed clothes retaining devices comprising an upwardly arched member secured to the rails or mattress of the bed adjacent 20 the head portion thereof, in combination with means on said member provided with elements adapted for detachable connection to the bed clothes.

7. Bed clothes retaining devices comprising an upwardly arched member secured to the rails or mattress of the bed adjacent 25 the head portion thereof, a member similarly secured to the rails or mattress adjacent the foot portion thereof, and means carried by 30 each of said members adapted to be detachably connected to the bed clothes.

In testimony whereof I affix my signature.
CHRISTIAN J. MEUNIER.
